UNITED STATES PATENT OFFICE.

FRANCIS M. SPEED, OF SAN FRANCISCO, CALIFORNIA, ASSIGNOR TO THE
TELPHERAGE ELECTRIC RAILWAY COMPANY, OF SAME PLACE.

ELECTRIC RAILWAY.

SPECIFICATION forming part of Letters Patent No. 380,060, dated March 27, 1888.

Application filed February 12, 1887. Serial No. 227,375. (No model.)

To all whom it may concern:

Be it known that I, FRANCIS M. SPEED, of the city and county of San Francisco, and State of California, have invented an Improvement 5 in Electric Railways; and I hereby declare the following to be a full, clear, and exact description thereof.

My invention relates to that class of electric railways in which the conductor is divided into 10 sections and has switches which normally bridge from one section to the other, and devices operated by the vehicle to move said switches successively and divert the current through the motors of said vehicle, so that the 15 motors are connected in series through the divided conductor.

My invention consists of an improved means for operating said switches and a peculiar arrangement of the conductors to permit of said. 20 switches being operated automatically without interference with the current operating the motors.

It further consists of a novel shuttle and connections with the vehicle for the purpose of 25 maintaining electrical connection between the motor which drives the vehicle and conductor either in a channel-way beneath the roadway or on supports above it and electrically operating the switches, all of which I shall herein- 30 after fully describe.

Referring to the accompanying drawings, Figure 1 is a side elevation showing the vehicle and its accompanying shuttle in the channel-way. Fig. 2 is a view showing the channel-way in cross-section, a portion being broken away, and the contained parts and traveling shuttle. Fig. 3 is a diagram of the electric system in its normal condition. Fig. 4 is a diagram of same, showing the motor in circuit.

40 A is the roadway, upon which travels the car B, carrying and propelled by an electric motor, (represented by X, Fig. 1.)

C is a channel-way in the roadway, having a slot, c, similar to the slot of a cable road.

45 D are parallel insulated non-conducting shuttle-guides and conductor-supports located in the channel-way.

E is a shuttle moved by the car, and fitted and traveling between the parallel insulated 50 shuttle-guides and conductor-supports D.

F is a divided and sectional conductor of the current operating the motors. One part is secured to the under side of one support and the other to the under side of the other support, and these parts are made in sections, which in 55 the diagram, Fig. 3, are designated by $f f' f''$, &c., on one side and by $f' f'' f'''$, &c., on the other side. The sections of the conductor on either support are electrically disconnected; but a section on one side is electrically connected with the succeeding section on the other side by wire G, as shown—that is, f with f'' , f' with f''' , f'' with f' , &c.

F' represents a dynamo supplying a current through the conductor F, for operating the 65 electro-motors X.

H is a divided and sectional conductor of a supplemental switch-operating current. This conductor is secured, one part to the upper side of one support D and the other to upper side 70 of the other support, and these parts are made in sections corresponding to those of the motor-circuit conductor F. These sections are shown in the diagram, Fig. 3, and are designated by $h h' h'' h'''$, &c., on one side and $h' h'' h''' h''''$, 75 &c., on the other side.

Wires I electrically connect each section on one side with the succeeding section on the other side at the point shown—that is to say, h with h' , h' with h'' , h'' with h''' , &c. 80

H' is a dynamo supplying a current to the supplementary circuit and operating the switches through the conductor H.

In addition to the connections of the conductor H by the wire I, the sections on one 85 side—namely, $h h' h'' h'''$, &c.—are electrically connected by wire j, which includes the coils of the electro-magnet J, and in addition to the electrical connection of the sections of the conductor F by the wire G the sections on one 90 side—namely, $f f' f'' f'''$, &c.—are electrically connected by wires k, forming a circuit which may be opened and closed at p and p' by the movement of the armature K of the electro-magnet J.

95 The operation of the system is as follows: The current from the dynamo H' passes through h , the wire j, and coils of the included electro-magnet J h'' , and by similar connections into h'' , and so on through each succeeding section 100

of one side of the conductor H, energizing the electro-magnet J, which, attracting its armatures K, closes the points $p p'$ and electrically connects section f, through the wire k, with f^2 , 5 and, by similar means, f^2 with f^4 , and so on through one side of the conductor F, Fig. 3. This is the normal condition of the system when no motors are in circuit—that is to say, the switch-circuit is complete through one side of 10 the conductor, and all of the armatures of the electro-magnets are attracted, the switches kept closed, and the motor-circuit uninterrupted through one side of the conductor F.

The body of the shuttle is made of wood or 15 other non-conducting material. It is supported, travels in, and is guided between the insulated non-conducting shuttle-guides and conductor-supports D. It is drawn along in that position by the metal draw-bars L² L³, 20 Fig. 1, which are pivoted to the car and to the upright metal rods L L'. These draw-bars are sufficiently long that they will occupy a sloping position with reference to the channel-way, the purpose of which is to prevent the up-and- 25 down movement of the car, caused by irregularities in the track, from being communicated to the shuttle. The rods L L' extend down through the slot c into the conduit C without touching the channel-irons, the guides below 30 and the guard-piece S (a little thicker than the rods L L') on the top of the shuttle preventing it. The metal rods L L' are insulated from each other by the non-conducting material of the body of the shuttle.

To each side of the lower portion of the shuttle is attached a metal plate, the right-hand plate being here designated by l and the left-hand plate by l'. These plates move under and in electrical connection with the parts 40 of the motor-circuit conductor F, directly above, by means of the springs, brushes, or other suitable yielding contacts, l² and l³, respectively, Fig. 2. The plates l l' are insulated from each other by the non-conducting 45 material of the body of the shuttle, but are each electrically connected with the rods L L' by wires l⁴ l⁵. It will be seen that a complete circuit may be established from one side of the conductor F through contacts l², plate l', wire 50 l⁵, rod L', into the motor, thence by the rod L, wire l⁴, contact l², plate l, into the other part of the conductor F, and this as the shuttle moves along; but in order to divert the current through the motor the motor-circuit must 55 be broken at $p p'$, Diagram 4, so that the current, instead of passing through the switch, as it normally does, will pass by the wire G to the other part of the conductor F, and thence through the parts of the shuttle and motor into 60 the other side of the conductor F. This is done by means of the metal contact-strip M M', transversely placed on the upper side of and insulated from all the other metal parts of the shuttle, and spanning the space between the 65 supports D and moving in contact with both sides of the switch-operating circuit-conductor H thereon.

Referring to the diagram, Fig. 4, it will be seen that when a motor, X, and its accompanying shuttle pass upon any section of the system a circuit of materially less resistance will be established from h, through the wire I, the part of the conductor h³, the contact-strips M M', to h², than that through the coils of the electro-magnet J. The magnet J, being cut 70 out or short-circuited, will release its armature, thus opening the switch-points $p p'$, breaking the normal motor-circuit, and diverting it from f, through G, into f³, thence, through the shuttle-contacts and the motor, to So 75 f². In other words, by means of a separate switch-operating current, the motor-circuit is kept normally whole throughout the system until when a car with its accompanying shuttle arrives upon any section of the system the 80 switches are automatically opened and the motor-current diverted from its normal course to that through the motors, as described, and this throughout the whole system. The metal strips l l', with the contact-brushes l² l³ thereon, 85 are made sufficiently long to span over the intervals between the sections of the motor-current conductor, and there are two of the metal contact-strips M M', the purpose of which is, that the forward one, M', may pass 90 onto a forward section and open its switch before the strip M has passed off of and closed the switch of the preceding section to prevent firing at the points $p p'$.

The switch is double-pointed to prevent an 90 arc forming (in case of derangement of the system) when the switch is closed or opened.

I am aware that it is not new, broadly, to provide for operating motors in series on an electric railway by opening and closing 105 switches (either mechanically or electrically) to divert the current through said motors; but there are serious objections to opening the switches mechanically, among which is the necessity of making the sections only as long as 110 the vehicle or train of vehicles. To accomplish it electrically with electro-magnets included in the motor-circuit adds too much resistance to that circuit, and interferes also with the proper government of the engine turning 115 the generator, the generator itself, and the motors.

By the use of a supplementary circuit and current the sections may be of any predetermined or of different lengths in the same system and the motor-current left uninterfered with.

Having thus described my invention, what I claim as new, and desire to secure by Letters Patent, is—

1. The combination of a main conductor for the main current, divided into sections, switches which normally bridge from one section to the other, traveling vehicles having electric motors by which they are driven, a 130 supplementary conductor for an independent current divided into sections corresponding to those of the main conductor, circuits containing electro-magnets normally bridging 135

from one section of said supplementary conductor to the other and keeping the switches closed, a contact moved by the vehicle and establishing electrical connection between the 5 main conductor and the motor on the vehicle, and a contact moved by the vehicle and in electrical connection with the supplementary conductor for shunting the electro-magnets successively of the supplementary or independent circuit, whereby the switches are opened and the main current diverted through the motors on the vehicles, and said motors connected in series, substantially as described.

2. The combination of a conductor divided 15 into sections, switches which normally bridge from one section to the other, traveling vehicles having electric motors by which they are driven, a supplementary conductor divided into sections, circuits containing electro-magnets which normally bridge from one section to the other of the supplementary conductor and keep the switches closed, and a contact device moved by the vehicle and establishing electrical connection between the main conductor 20 and the motor on the vehicle and moving in electrical contact with the supplementary conductor, whereby the supplementary current is shunted through the shuttle, the switches opened, and the main current diverted through the motors on the vehicles, so 25 that said motors are connected in series, substantially as described.

3. In an electric railway having a sectional main-current conductor, the sections of which 35 are bridged by switches, and a sectional supplementary current-conductor having its sections connected by circuits containing electro-magnets, which hold the switches normally closed, a shuttle moved by the traveling vehicle, said shuttle having the double function 40 of establishing a circuit from each successive section of the main conductor through the motor on the traveling vehicle, and of short-circuiting the supplementary current, whereby 45 the magnets are cut out and the switches opened to divert the main current through the motors, substantially as described.

4. The combination of a longitudinally-divided conductor, the parts of which extend 50 parallel along an electric railway, said parts being divided into sections of any desired length, each section on one given side being connected with the succeeding section on the opposite side, switches which normally bridge 55 from one section on said given side to the succeeding section on the same side, a supplementary longitudinally-divided conductor, the parts of which extend parallel along the road, said parts being divided into sections corresponding in length to the sections of the main 60

conductor, each section on one given side being connected with the succeeding section on the opposite side, circuits containing electro-magnets connecting successive sections on said given side and operating the switches, 65 and a shuttle or other contact device moved by the vehicle, said shuttle establishing electric connection between the motor on the vehicle and the main conductor, and moving in electrical contact with the supplementary conductor, whereby the switches are operated successively and the main current diverted through the motors on the vehicles, substantially as described.

5. In an electric railway, the combination 75 of the parallel insulated non-conducting shuttle-guides D, the divided and sectional main conductor under said guides, opposite successive sections being connected, as described, the electric switches connecting the sections 80 on the same side, the divided and sectional supplementary conductor on top of the guides, opposite successive sections being connected, as described, the circuits containing electro-magnets bridging the sections of the supplementary conductor on the same side and keeping the switches closed, and the shuttle moved by the vehicle and traveling between and supported by the guides, said shuttle having electrical contact below with the main conductor 85 and above with supplementary conductor, 90 substantially as described.

6. In an electric railway, the combination 95 of the parallel insulated non-conducting shuttle-guides D, the divided and sectional main conductor under said guides, opposite successive sections being connected, as described, the electric switches connecting the sections on the same side, the divided and sectional supplementary conductor on top of the guides, 100 opposite successive sections being connected, as described, the circuits containing electro-magnets bridging the sections of the supplementary conductor on the same side and keeping the switches closed, and the shuttle moved 105 by the vehicle and traveling between and supported by the guides, said shuttle having the contacts below moving in electrical connection with the main conductor, and the cross-contacts M M' above, one in advance of the other, 110 and spanning the space between the sides of the supplementary conductor and moving thereon, substantially as described.

In witness whereof I have hereunto set my hand.

FRANCIS M. SPEED.
